UNITED STATES PATENT OFFICE.

WILLIAM M. PLAISTED, OF LARCHMONT, NEW YORK, ASSIGNOR TO HAZELTON BROTHERS, OF NEW YORK, N. Y., A CORPORATION OF NEW YORK.

DESIGN FOR A PIANO-CASE.

50,794.

Specification for Design.

Patented May 15, 1917.

Application filed March 8, 1917. Serial No. 153,509. Term of patent 3½ years.

To all whom it may concern:

Be it known that I, WILLIAM M. PLAISTED, a citizen of the United States, residing at Larchmont Manor, in the county of Westchester and State of New York, have invented a new, original, and ornamental Design for a Piano-Case, of which the following is a specification, reference being had to the accompanying drawing, forming part of this specification, which is a perspective view of a case for a piano, showing my new design.

I claim:—

The ornamental design for a piano case as shown.

In testimony whereof I have hereunto affixed my signature.

WILLIAM M. PLAISTED.
